UNITED STATES PATENT OFFICE.

FERDINAND FRANKE, OF CLARK COUNTY, INDIANA.

METHOD OF FILLING MATTRESSES.

No. 891,830.

Specification of Letters Patent. Patented June 30, 1908.

Application filed November 10, 1904. Serial No. 232,217.

To all whom it may concern:

Be it known that I, FERDINAND FRANKE, a citizen of the United States, residing on Rural Free Delivery Route No. 1, in the county 5 of Clark and State of Indiana, have invented a new and useful Method of Filling Mattresses, of which the following is a specification.

My invention relates to the manufacture of 10 mattresses and has for its object the provision of an improved method of filling said mattresses, whereby the filling material of cotton, down, feathers, or the like, will be deposited in a layer of uniform thickness and 15 without lumps.

These objects I attain by means of the mechanism illustrated in the accompanying drawing which represents the embodiment of my invention in a perspective view, showing 20 parts broken away to show the internal working parts, and the bedtick in section so as to show the manner of depositing the fiber.

1 represents the frame of the machine; 2, the drum of the picker; 3, the blower; 4, the 25 air tube; 5, the feed belt conveyer; 6, a bedtick; 7, the flange on air tube 4; and, 8, the picked fiber deposited in the bedtick. The drum 2 is studded with teeth sharpened at their outer ends and slanted slightly in the 30 direction of motion. The fiber in lumped and packed condition is scattered upon the belt conveyer 5 and is fed to corrugated rollers of small diameter of the form usual in such apparatus and not illustrated in the 35 drawing, disposed parallel with and immediately behind drum 2 and as close as practicable to the ends of the picker teeth. The drum 2 is covered with a hood. The floor of hood 9, immediately under drum 2, is provided with an opening, which is connected by 40 means of a tube 10, with the center of blower 3. The blower 3 is located preferably just below drum 2 and hood 9 and is preferably of the conventional centrifugal type, inclosed 45 with a casing 11. The delivery-opening of the blower may be toward the front of the machine and is provided with a tube 4. At the outer end of this tube is a sheet metal collar, 7, over which the bedtick is fastened. 50 The tube 4 is located about 12 or 18 inches

above the floor upon which the machine rests in order that the bedtick attached thereto may lie flat upon the floor when inflated in the process of filling, as shown in the drawing. The bedtick 6 is sewed up, with the exception of a small slit or open seam left in the middle of one end in order that it may be slipped over collar 7.

The operation of the machine will now be readily understood. The fiber to be picked 60 is placed upon the belt conveyer 5 and fed to the corrugated rollers, by which it is rolled in and held fast in proximity to the rapidly revolving pointed teeth of the drum. The teeth tear the material into fine bits and 65 shreds, and the centrifugal force, due to the rapid rotation of the drum, together with the suction produced by blower 3, causes the picked fiber to fly from the teeth. When the picked fiber reaches the floor of hood 9 it 70 is drawn through the opening and tube 10 into blower 3 along with the air that has been drawn in through hood 9. Then the mixture of air and fiber is forcibly blown through tube 4 into the bedtick. In the bed- 75 tick the fiber suspended in the air circulates about, and, as the air is forced through the interstices of the ticking, the fiber settles down upon every portion of the side of the bedtick adjacent to the floor, even in the 80 sharpest corners. The quantity of fiber to be used to fill a bedtick is first weighed before it is fed into the machine, and thus uniform filling is attained. Heretofore it has been difficult to avoid a wadded and lumpy condition of the filling of bedticks filled with fiber, 85 and the corners of the tick could not be properly filled out, but with my improvement the filling is perfectly uniform, the corners being perfectly filled out. Heretofore, also, with 90 the conventional stuffing machines, it has been necessary to leave an entire end of the tick open to be sewed up after it was filled, but I leave only a small portion to be sewed 95 after the filling has been injected.

Having thus described my invention so that any one skilled in the art pertaining thereto may make and use it, I claim—

1. The herein described method of forming mattresses which consists of directing an 100

air blast into the tick of the mattress to inflate it and discharging the filling material into said tick along with said air blast.

2. The herein described method of forming mattresses which consists of conducting an air blast from the discharge pipe of a picker directly into a mattress tick whereby

said tick is inflated, and delivering the filling material in a layer of uniform thickness, into the mattress while so inflated.

FERDINAND FRANKE.
